UNITED STATES PATENT OFFICE.

CHARLES W. SMITH, OF EVANS, NEW YORK.

IMPROVEMENT IN IGNITING-FUSES FOR SHELLS.

Specification forming part of Letters Patent No. 43,801, dated August 9, 1864; antedated February 1, 1864.

To all whom it may concern:

Be it known that I, CHARLES W. SMITH, of the town of Evans, in the county of Erie and State of New York, have invented a new Fuse-Lighter for Rendering more Certain the Ignition of Fuses in Ordnance-Shells; and I do hereby declare that the following is a full description thereof, reference being had to the accompanying drawings, making part of this specification.

My invention consists in a separate primer to be attached to the ordinary time-fuse of an explosive ordnance-shell, to secure the more certain ignition of such fuses than when fired in the ordinary manner.

My invention is more particularly applicable to that class of projectiles intended for use with rifled ordnance, as the gases are in most of these prevented, by the closing of the windage, from passing around the shell in sufficient amount to ignite the fuse with certainty. By the use of a primer, however, formed of some substance igniting at a lower temperature than fuse composition or common gunpowder the fuse will be ignited much more readily, and there are peculiar advantages arising from the use of an igniter made separate and distinct from the fuse itself, as will be hereinafter enumerated.

To enable others skilled in the art to make and use my invention, I will proceed to describe its construction and operation.

These primers may be made of gun-cotton, gun-paper, or any other form of pyroxyline, or percussion-powder or other suitable fulminate cemented upon a wafer of dry collodion; but the mode of construction I prefer is as follows: I take a thin wafer of collodion half an inch in diameter and cement upon it with collodion in the fluid state a wisp of gun-cotton prepared with a strong nitric acid, so as to ignite at a low temperature. This form of primer is shown in Figure 1, and at Fig. 2 may be seen one formed by cementing fulminating-powder upon a wafer in a similar manner. These primers may be pressed in the end of the fuse-plug after the fuse has been cut off the proper length and inserted, and held by the friction against the sides of the plug; but I prefer to attach them by means of

two small pins, *a a*, adapted to be thrust in the paper covering of the fuse. Fig. 3—in which A represents the body of the shell, B the wooden fuse-plug, C an ordinary paper-case time-fuse, and D one of my primers—will illustrate this mode of attachment. The primers may be carried in a small box in the pocket and be attached to the fuse just previous to the insertion of the shell in the gun.

I am aware that it has been common to fix a priming of powder permanently to the end of a fuse by means of an adhesive substance at the time of manufacture, and that pieces of quick-match have been also thus attached; but a priming thus made and forming a part of the fuse has some serious difficulties. Artillerists frequently wish to alter the rate of burning of a fuse after it is driven in the shell, and they are accustomed to do this by gouging or hollowing out the end of the fuse itself. When the priming is permanently attached, it will by this operation be necessarily removed, while my primer is open to no such objection. Again, my primers may be made of a material that will ignite at a much lower temperature than would be safe were they permanently attached. They may also be so made as to spread outside the end of the fuse-plug, and thus be more certainly ignited, care being taken to use a concave rammer-head to avoid their taking fire by its percussion. It is evident that these primers may be made in a variety of forms and of various materials. I do not limit myself to the form or to the precise mode of attachment shown and described. Neither do I wish, on the other hand, to be understood as claiming any primer, match, or apparatus which is permanently attached.

Having now fully described my invention, what I claim as new therein, and desire to secure by Letters Patent, is—

A portable fuse-primer adapted to be transported separately and to be attached at the end of a time-fuse just previous to the insertion of the shell in the gun, for the purpose of igniting the fuse at the moment of discharge.

CHAS. W. SMITH.
